(57) **CLAIM**

The ornamental design for a wetness sensor, as shown and described.

DESCRIPTION

FIG. 1 is a top, front, left perspective view of an embodiment of a wetness sensor embodying our new design.

FIG. 2 is a front elevational view of the sensor shown in FIG. 1.

FIG. 3 is a rear elevational view of the sensor shown in FIG. 1.

FIG. 4 is a left side elevational view of the sensor shown in FIG. 1.

FIG. 5 is a right side elevational view of the sensor shown in FIG. 1.

FIG. 6 is a top plan view of the sensor shown in FIG. 1; and, FIG. 7 is a bottom plan view of the sensor shown in FIG. 1. The broken lines in the drawings represent unclaimed environmental subject matter and form no part of the claim.
